[57] CLAIM

The ornamental design for a winch housing, as shown and described.

DESCRIPTION

FIG. 1 is a perspective view of a winch housing showing our new design;

FIG. 2 is a side elevational view thereof, the opposite side being a mirror image of the side shown;

FIG. 3 is a front elevational view thereof;

FIG. 4 is a top plan view thereof;

FIG. 5 is a bottom plan view thereof; and,

FIG. 6 is a rear elevational view thereof.

The broken lines are for illustrative purposes only, and form no part of the claimed design.
